STOCKING

Clarence David Goff, Philadelphia, Pa.

Application October 20, 1950, Serial No. 12,637

Term of patent 14 years

(Cl. D47—7)

To all whom it may concern:

Be it known that I, Clarence David Goff, a citizen of the United States, and a resident of Philadelphia, county of Philadelphia, State of Pennsylvania, have invented a new, original, and ornamental Design for a Stocking, of which the following is a specification, reference being had to the accompanying drawings, forming a part thereof, wherein:

The figure is a side elevational view of the stocking, showing my new design.

I claim:

The ornamental design for a stocking, as shown.
CLARENCE DAVID GOFF.
